UNITED STATES PATENT OFFICE

2,505,598

WINDOW LATCH

John W. Wexler, Silver Spring, Md.

Application April 9, 1947, Serial No. 740,296

7 Claims. (Cl. 292—145)

1

This invention relates to window latch devices, and more particularly, to window latches of the sliding type.

A main object of the invention is to provide a novel and improved window latch device which is very simple in construction, easy to install, and which provides reliable securement of windows in fully closed or in partly closed positions.

A further object of the invention is to provide an improved window latch device which is very inexpensive to manufacture, neat in appearance and sturdy in construction.

A still further object of the invention is to provide an improved window latch device which may be fabricated from relatively light gauge sheet metal, yet by virtue of its configuration, is extremely rigid and able to resist powerful forces exerted thereon.

A still further object of the invention is to provide an improved window latch device of the sliding lock type wherein safety locking means are incorporated in the latch device, permitting said latch device to be manipulated from inside the window to lock or unlock same but preventing the latch device from being released from its locking position by shaking the window sash from outside the window.

Further objects and advantages of the invention will become apparent from the following description and claims, and from the accompanying drawings, wherein:

Figure 1 is a fragmentary elevational view of a portion of a window structure showing a window sash locking device installed thereon in accordance with the present invention.

Figure 2 is an enlarged horizontal cross-sectional detail view taken on line 2—2 of Figure 1.

Figure 3 is a vertical cross-sectional detail view taken on line 3—3 of Figure 2.

Figure 4 is a vertical cross-sectional view taken on line 4—4 of Figure 2.

Figure 5 is an enlarged detail plan view of a base element employed in the latch structure of the present invention.

Figure 6 is an end elevational view of the base element of Figure 5.

Figure 7 is an enlarged perspective detail view of a sliding latch member employed with the base element of Figure 6.

Figure 8 is a vertical cross-sectional view similar to Figure 3 but showing a modified form of the latch structure according to this invention.

Figure 9 is an enlarged perspective detail view of a sliding latch member employed in the latch structure of Figure 8.

Referring to the drawings, 14 designates a conventional window sash having a top sash member 12 and a bottom sash member 13. Designated at 14 is a vertical side member of the window frame. The vertical side members of the window frame are provided with conventional vertical guide

2

ways in which the sash members 12 and 13 are slidably received.

Secured to the top meeting rail 15 of lower sash member 13 adjacent the vertical side member 14, as by round-headed screws 16, 16, is a base member 17, shown in Figures 5 and 6, which has a generally rectangular bottom portion 18 formed with fastening apertures 19, 19 and having in-turned side flanges 20, 20 defining lateral guide ways. Slidably mounted on bottom portion 18 is a latch member 21 having a base portion 22 provided with laterally projecting horizontal side flanges 23, 23 slidably received in the lateral guide ways defined by the in-turned side flanges 20, 20 of the base member 17. The intermediate portion of base 22 is formed with a smoothly curved corrugation 24 extending parallel to the lateral side flanges 23, 23 and for the full length of the base 22. Corrugation 24 imparts substantial stiffness to the base 22 against bending forces acting at the ends of the base member. At one end of the base 22 is a vertically projecting detent member 25 having smoothly rounded upwardly tapering side edges 26, 26. The detent member 25 is formed at its top with a rounded seat 27. The top portion of detent member 25 is preferably tapered in thickness so that its thickness at seat 27 is relatively reduced with respect to the thickness of the main body portion thereof. The bottom side portions of detent member 25 are notched, as shown at 28, 28 to provide sliding clearance for the in-turned guide flanges 20, 20 when the detent member is retracted. The intermediate portion of detent member 25 is formed with a substantially circular opening 29 having vertical opposed slot portions 30, 30 connecting therewith.

At the other end of the base 22 is a vertical lug 31 of a width small enough to be received between the opposed edges of the guide flanges 20, 20 when the latch member is moved inwardly to a latching position. Lug 31 functions as a manual grip or handle for the latch member.

The concave recess beneath corrugation 24 provides sliding clearance for the heads of the screws 16, 16 employed to secure the base 17 to meeting rail 15.

Vertically aligned with the latch member 21 and screwed into the side stile 32 of upper sash 12 are a plurality of flat-headed screws shown at 33, the lowermost screw being positioned just above the level of seat 27 of the detent member 25 when the upper sash 12 is in its fully raised position with respect to lower sash 13. The heads of the screws 33 project outwardly from stile 32 a distance slightly greater than the thickness of detent member 25, so that said heads may overlap the outer surface of the detent member when it is in locking position.

To lock the window in fully closed position,

latch member 21 is pushed inwardly so that detent member 25 abuts the stile 32 and seat 27 underlies the lowermost screw 33. Upper sash 12 is then slightly lowered so that the head of said lowermost screw overlaps the outer surface of detent member 25 and the screw shank is received in seat 27. To lock the window in a partly opened position, the detent member 25 is engaged with one of the screws 33 through the intermediate circular opening 29 therein and the sash is then slightly adjusted so that the screw shank is engaged in one of the vertical slot portions 30. If an attempt is made from the outside to further open the window by moving the sash up or down, the screw shank engages in one or the other of the slot portions 30 and prevents release of the detent member 25 by shaking the sash. To disengage the detent member, the screw head must be centered in the circular opening 29, and this can only be done from inside the window.

By tapering the top portion of detent member 25 in thickness, engagement of the seat 27 under the head of the lowermost screw 33 is facilitated.

It will be noted that the latch member 21 is such that it may be fabricated from a single piece of relatively light sheet metal stock, and by providing the corrugation 24 the stiffness of the base 22 is made great enough to resist any bending forces which might be applied to the latch member when an unauthorized attempt is made to open the window.

In the embodiment disclosed in Figures 8 and 9, the same base member 17 is employed as in the embodiment of Figures 1 to 7. The latch member, shown at 21', has a base 22' identical with base 22 of the former embodiment and a handle lug 31' also similar to handle lug 31. The detent portion 25' is generally similar in configuration to detent portion 25 except that it has no top seat corresponding to seat 27, nor does it have an intermediate locking aperture. Instead it has secured to its intermediate portion an outwardly projecting detent lug 34 which may be of square, round, or any other suitable cross-sectional shape. The stile 32 of the upper window sash is formed with a plurality of spaced recesses vertically aligned with the lug 34, and secured in each of said recesses is a metal socket member 35 having an internal cavity adapted to slidably receive the lug 34, said cavity being preferably of the same cross-sectional shape as said lug. To lock the window, the latch member 21' is merely pushed inwardly to engage the lug 34 in a selected socket member 35.

While certain specific embodiments of a window latching device have been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. In a window latch device, a latch member formed from a single piece of sheet metal and comprising a base portion having horizontal parallel side flanges and formed intermediate said flanges with an arcuate corrugation concave at its bottom surface and extending parallel to said side flanges, a detent element projecting upwardly from the forward end of said base portion and formed with a generally circular opening having opposed vertical slot portions, and a

lug projecting upwardly from the rear end of said base portion.

2. In a window latch device, a latch member comprising a base portion having horizontal parallel side flanges and formed intermediate said flanges with a corrugation concave at its bottom surface and extending substantially parallel to said side flanges, a detent element projecting upwardly from the forward end of said base portion, the top of said detent element being formed with a notch and the body of said detent element being formed with an opening having opposed vertical slot portions, said slot portions being substantially vertically aligned with said notch.

3. In a window latch device, a latch member formed from a single piece of sheet metal and comprising a base portion having horizontal parallel side flanges and formed intermediate said flanges with an arcuate corrugation concave at its bottom surface and extending substantially parallel to said side flanges, a detent element projecting upwardly from the forward end of said base portion and having smoothly curved upwardly tapering side edges, the top of said detent element being formed with an arcuate notch and the body of said detent element being formed with a generally circular opening vertically aligned with said notch and having opposed vertical slot portions, and a lug projecting upwardly from the rear end of said base portion.

4. In a window latch device, a latch member comprising a base portion having a detent element projecting upwardly from an end thereof, said detent element being formed with an opening having at least one vertical slot portion and being formed at its top edge above said opening with a notch.

5. In a window latch device, a latch member comprising a base portion having substantially parallel side edges and having a detent element projecting upwardly from an end thereof, said detent element being formed with a generally circular opening having at least one vertical slot portion and being formed at its top edge above said opening with a notch.

6. In a window latch device, a latch member comprising a base portion having a detent element projecting upwardly from an end thereof, said detent element being formed with a generally circular opening having opposed vertical slot portions and being formed at its top edge above said opening with a notch.

7. In a window latch device, a latch member formed from a single piece of sheet metal and comprising a base portion having substantially parallel side edges, a detent element projecting upwardly from the forward end of said base portion and formed with a generally circular opening having opposed vertical slot portions and being formed at its top edge above said opening with a notch, and a lug projecting upwardly from the rear end of said base portion.

JOHN W. WEXLER.
